UNITED STATES PATENT OFFICE

2,497,602

CLAMP CONNECTOR

Curtis L. Hatch, Salt Lake City, Utah, assignor of
one-third to Edwin D. Hatch, Salt Lake City,
Utah

Application April 1, 1948, Serial No. 18,385

2 Claims. (Cl. 173—259)

1

This invention relates to new and useful improvements and structural refinements in clamp connectors, more specifically, connectors such as may be conveniently and effectively employed for attaching electrical conduits to substantially cylindrical rods or posts, and the principal object of the invention is to facilitate convenient and a dependable connection between a cable and a terminal post of a storage battery used in automobiles and similar vehicles.

However, it should be understood that the application of the invention is by no means restricted to this particular use, and that the invention may be employed wherever a cable, or the like, is to be connected to a substantially cylindrical member, as will be readily apparent from the following disclosure.

In any event, the principal object of the invention as above outlined is achieved by the provision of an externally threaded bushing to which the cable is connected in a more-or-less conventional manner and which is receivable on the battery post, this bushing including a gripping pad and being provided with a clamping nut engageable with the pad, whereby the latter is urged in frictional engagement with the post of the battery to which the aforementioned cable is to be electrically connected.

An important feature of the invention resides in its simplicity of construction, ease of manufacture, and in its adaptability for repeated use.

With the above more important objects and features in view and such other objects and features as may become apparent as this specification proceeds, the invention consists essentially of the arrangement and construction of parts as illustrated in the accompanying drawings, in which:

Figure 1 is a top plan view of the invention;

Figure 2 is a cross sectional view, taken substantially in the plane of the line 2—2 in Figure 1;

Figure 3 is a perspective view of the bushing, cable socket and gripping pad used in the invention;

Figure 4 is a perspective view of a clamping nut used therein; and,

Figure 5 is a perspective view of the gripping pad per se.

Like characters of reference are employed to designate like parts in the specification and throughout the several views.

Referring now to the accompanying drawings in detail, the invention consists of a clamp connector designated generally by the reference char-

acter 10, the same embodying in its construction a bushing 12 which is receivable on the terminal post of the battery (not shown) and which is externally screw-threaded as at 14.

The bushing 12 preferably is formed with an integral, polygonal wrench-receiving portion 16, and it will be also noted that the bushing is provided in the side wall thereof with a recess 18 which extends into the bushing portion 16, as is best shown in Figure 2.

A wedge-shaped gripping pad 20 is provided in a relatively large end portion thereof with a transverse bore 22 to accommodate a pin 24, the latter being journaled in the portion 16 of the bushing 14 and the pad being pivotally disposed, so to speak, in the recess 18 of the bushing, as will be clearly apparent.

It is to be noted that the pad 20 includes what may be referred to as a cam surface 26 on one side, and a set of gripping teeth 28 on the relatively opposite side, these teeth being projectable into the bore 30 of the bushing 12, as shown in Figure 2.

A clamping nut 32 is receivable on the screw-threaded portion of the bushing 14 and is engageable with the cam surface 26 of the pad 20, whereby the pad is urged inwardly, into the bore 30.

A suitable socket 34 of more-or-less conventional design is rigidly secured in any suitable manner to the portion 16 of the bushing 14, the socket 34, of course, being intended to receive the electrical cable which is to be connected.

The connecting operation is effected by simply placing the bushing 14 on the battery terminal post and thereafter tightening the nut 32 and the latter, by virtue of its engagement with the cam surface of the pad 20, will urge the teeth 28 of the pad in frictional engagement with the terminal post of the battery, thereby firmly and securely retaining the clamp connector on the battery post, as will be clearly understood.

Needless to say, the clamp connector may be readily removed or separated from the battery post by simply loosening the clamping nut 32.

It is believed that the advantages and use of the invention will be clearly apparent from the foregoing disclosure, and, according, further description thereof at this point is deemed unnecessary.

While in the foregoing there has been shown and described the preferred embodiment of this invention, it is to be understood that minor changes in the details of construction, combination and arrangement of parts may be resorted

to without departing from the spirit and scope of the invention as claimed.

Having described the invention, what is claimed as new is:

1. In a clamp connector, the combination of an externally screw-threaded bushing provided at one end thereof with an outturned flange, said bushing including said flange being formed with an open slot, a pin provided in said flange and extending transversely of said slot in a plane outside the screw-threaded surface of the bushing, a wedge-shaped gripping dog pivotally mounted in said slot on said pin, said dog having an outer surface extending inwardly in said slot beyond the screw-threaded surface of the bushing, and a clamping nut provided on said bushing and engageable with the outer surface of said dog whereby the latter may be urged into the bushing.

2. In association with a battery post, a clamp connector comprising a screw-threaded bushing

positionable on said post and formed with an open slot, a wedge-shaped dog pivotally mounted in said slot and provided on its inner surface with a set of gripping teeth, and a clamping nut provided on said bushing and engageable with said dog whereby said teeth may be urged in engagement with said post.

CURTIS L. HATCH.
